US00D780114S

(12) **United States Design Patent** (10) Patent No.: **US D780,114 S**
(45) Date of Patent: **** Feb. 28, 2017**

(54) **USB CHARGER BASE**

- (71) Applicant: **Chao-Yu Yueh**, Taipei (TW)
(72) Inventor: **Chao-Yu Yueh**, Taipei (TW)
(73) Assignee: **FUTUREPATH TECHNOLOGY (SHENZHEN) CO., LTD.**, Shenzhen (CN)
(**) Term: **14 Years**
(21) Appl. No.: **29/521,447**
(22) Filed: **Mar. 24, 2015**

(30) **Foreign Application Priority Data**

- Dec. 18, 2014 (TW) 103307451

Primary Examiner — Rosemary K Tarcza*Assistant Examiner* — Nathaniel D Buckner*(74) Attorney, Agent, or Firm* — McClure, Qualey & Rodack, LLP(57) **CLAIM**

The ornamental design for a USB charger base, as shown and described.

DESCRIPTION

FIG. 1 is a perspective view of a USB charger base, showing my new design;

FIG. 2 is a bottom perspective view for the USB charger base;

FIG. 3 is a top plan view of the USB charger base;

FIG. 4 is a bottom plan view of the USB charger base;

FIG. 5 is a left side view of the USB charger base;

FIG. 6 is a right side view for the USB charger base;

FIG. 7 is a rear view of the USB charger base; and,

FIG. 8 is a front view of the USB charger base.

1 Claim, 5 Drawing Sheets
